(57) CLAIM

The ornamental design for an umbrella canopy, as shown and described.

DESCRIPTION

FIG. 1 is a top view of the umbrella canopy design according to my invention showing six (6) rib and strut members alternating in height, wherein the lengths of each rib are the same;

FIG. 2 is a front view of the umbrella canopy design shown in FIG. 1 according to my invention;

FIG. 3 is a left side view thereof;

FIG. 4 is a right side view thereof;

FIG. 5 is a bottom view thereof; and,

FIG. 6 is a rear view thereof.
